UNITED STATES PATENT OFFICE.

JAMES M. DENNING, OF CONNEAUT, OHIO, ASSIGNOR TO THE CONNEAUT SHOVEL COMPANY, OF CONNEAUT, OHIO, A CORPORATION OF OHIO.

MACHINE FOR MAKING SHOVELS.

Application filed September 15, 1925. Serial No. 56,484.

The present improvements relate more particularly to mechanism for spreading the tangs and forming the socket in plain back shovels. As the manufacture of such shovels is at present carried out, a drop hammer or press is employed to form the shovel proper and a hand sledge and mandrel are used to thus spread the tangs and form the socket.

10 The object of the present invention is to provide an attachment for the drop hammer or press in which the blade of the shovel is thus formed, whereby the other steps of the operation just described may be automatically performed, thereby eliminating all hand work and at the same time increasing the rate of production.

To the accomplishment of the foregoing and related ends, the invention, then, consists of the means hereinafter fully described and particularly pointed out in the claims, the annexed drawings and the following description setting forth in detail certain mechanism embodying the invention, such disclosed means constituting, however, but one of the various mechanical forms in which the principle of the invention may be used.

In said annexed drawings:—

30 Fig. 1 is a plan view of a machine embodying my present improvements; Fig. 2 is a side elevation of such machine; Fig. 3 is an end elevation as viewed from the right in Figs. 1 and 2; Fig. 4 is a plan view of the shovel blank upon which the machine is designed to operate; Fig. 5 is a longitudinal section of such blank, the plane of the section being indicated by the line 5—5, Fig. 4; Fig. 6 is a plan view of the shovel 40 as it comes from the machine; and Figs. 7 and 8 are respectively a longitudinal section and a transverse section of such shovel, the planes of such section being indicated by the lines 7—7 and 8—8, Fig. 6.

45 As previously indicated, the mechanism that constitutes the present improvement may be added as an attachment to a drop hammer or press of standard type, such as has heretofore been employed to form the flat shovel blank into a blade of desired shape. In the illustrated embodiment of the invention, it has accordingly been considered unnecessary to show more than the bed 1 and vertical guides 2 of such drop hammer. Resting on such bed is the lower

die 3, while the upper die 4 is reciprocably held between said guides 2, suitable mechanism (not shown) being provided to raise the same to the proper height and then allow it to drop onto the lower die. Such dies, 60 it will be noted, are disposed so as to open toward the back, i. e. the right of the machine, as illustrated in Figs. 1, 2 and 3, instead of to the front as ordinarily.

Firmly secured, as by means of bolts 5, 65 to such back or right hand side of bed 1 is a supplemental bed or frame 6, it being noted that the latter is formed with vertical ribs 7 that enter corresponding grooves 8 cut in bed 1 so that said frame 6 may be 70 adjusted vertically with respect to bed 1 and still be held in proper alignment therewith.

Mounted on the upper face of frame 1, so as to be reciprocable towards and from dies 75 3 and 4, is a slide 10 suitably held in guides 11 and connected by means of a pitman 12 with a motor driven crank shaft 13, whereby reciprocation of the slide is produced. Oscillatory attached to the slide about a 80 transverse axis, which is conveniently the same axis as that of the pin 14, whereby pitman 12 is attached to the slide, is a forwardly projecting plunger or ram 15. The latter rests at an intermediate point on an 85 adjustable spring support 16 whereby its forward end, i. e., the end that projects towards the dies, may be raised or lowered so as to be centered more or less exactly with a complementary recess 17 in the juxtaposed 90 face of the dies. This recess, one-half of which it will be understood is formed in each of the two meeting faces of the dies, is located to receive the socket portion *a* of the shovel blank A (see Figs. 4 and 5), while 95 the tangs *a'* will project rearwardly from the dies. The forward end of the plunger 15 is so shaped that when entered between such tangs and forced into such socket portion of the blank, the tangs will be spread 100 apart and the socket given the proper cross-sectional form, as shown in Figs. 6, 7 and 8.

In operation, the flat blank, as shown in Figs. 4 and 5, is placed in proper position on the lower die 3 with the straps or tangs extending to the rear, it being understood that at this stage the plunger 15 is completely retracted, such plunger being shown in an intermediate position in its path of travel in the several figures of the drawings. 110

Thereupon the hammer is caused to drop, bringing the upper die 4 into forceful contact with the blank on the lower die, and as soon as such upper die has thus seated, the mechanism for reciprocating the slide 10 is set in motion through a suitable trip lever 20, as need not be explained in detail. The plunger 15 is thus advanced towards the drop hammer, going in just far enough to 10 spread the tangs and form the socket, following which it is returned to its normal position. The hammer is now opened by raising die 4 and the shovel blade properly shaped and with its socket properly opened 15 and formed is removed and a fresh blank substituted therefor.

From the foregoing, it will be seen that my improved mechanism may be readily applied as an attachment to existing drop 20 hammers such as are at present used in the manufacture of shovel blades. The dies of the drop hammer remain just as accessible as before for insertion of the shovel blank and removal of the finished blade, and the 25 operation of spreading the tangs and forming the socket is quickly and easily carried out without requiring the operator to change his position. Furthermore, it is possible to make all of the sockets of exactly the same 30 depth since the stroke of the plunger 15 may be accurately gauged and the uncertainty of the old hand operation is thus entirely eliminated.

Other modes of applying the principle of 35 my invention may be employed instead of the one explained, change being made as regards the mechanism herein disclosed, provided the means stated by any of the following claims or the equivalent of such 40 stated means be employed.

I therefore particularly point out and distinctly claim as my invention:—

1. In a shovel making machine, the combination with a stationary lower die and vertically reciprocable upper die adapted 45 to form a flat blank into a blade of desired shape; of a plunger reciprocable transverse-

ly of said dies, said plunger being adapted to enter between the tangs of such blank to spread the same and form the socket; and 50 a spring supporting said plunger and serving as a guide therefor.

2. In a shovel making machine, the combination with a drop hammer equipped with a stationary lower die and vertically reciprocable upper die adapted to form a flat shovel blank into a blade of desired shape; a supplemental bed attached to the rear side of said drop hammer; a slide on said bed reciprocable transversely of said dies; and 55 a plunger pivoted at one end to said slide and having its other end formed to enter between the tangs of such blank to spread the same and form the socket.

3. In a shovel making machine, the combination with a drop hammer equipped with a stationary lower die and vertically reciprocable upper die adapted to form a flat shovel blank into a blade of desired shape; a supplemental bed attached to the 60 rear side of said drop hammer; a slide on said bed reciprocable transversely of said dies; a plunger pivoted about a horizontal axis at one end to said slide and having its other end formed to enter between the tangs of such blank to spread the same and form the socket; and an adjustable support serving 65 as a guide for said plunger.

4. In a shovel making machine, the combination with a drop hammer equipped with a stationary lower die and vertically reciprocable upper die adapted to form a flat shovel blank into a blade of desired shape; a supplemental bed vertically adjustably attached to the rear side of said drop hammer; a slide on said bed reciprocable transversely of said dies; and a plunger carried 70 by said slide and adapted to enter between the tangs of such blank to spread the same and form the socket.

Signed by me this 12th day of September, 90 1925.

JAMES M. DENNING.
